(57) **CLAIM**

The ornamental design for a flashlight, as shown and described.

DESCRIPTION

FIG. 1 is a front, left and top perspective view of a flashlight, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion of FIG. 1 thereof; and,

FIG. 10 is an enlarged view of portion of FIG. 2 thereof.

The dot-dash broken lines in FIGS. 1-2 and 9-10 are for the purpose of annotating the enlargements only and form no part of the claimed design.

The evenly spaced broken lines immediately adjacent the shade lines depict the bounds of the claimed design, while all other evenly spaced broken lines depict portions of the flashlight that form no part of the claimed design.
